United States Patent Office

Des. 227,363

Patented June 19, 1973

227,363

SPOUT END

Donald M. Genaro, Haworth, N.J., and Charles W. Pelly, Scarsdale, N.Y., assignors to American Standard Inc., New York, N.Y.

Filed Mar. 6, 1972, Ser. No. 232,349

Term of patent 14 years

Int. Cl. D23—01

U.S. Cl. D23—32

FIG. 2

FIG. 5

FIG. 1

3

3

FIG. 4

FIG. 3

FIG. 1 is a side elevational view of a spout end embodying my new design;

FIG. 2 is a top plan view thereof;

FIG. 3 is a bottom plan view thereof taken along the line 3—3 of FIG. 1;

FIG. 4 is a rear elevational view thereof, and

FIG. 5 is a front elevational view thereof.

I claim:

The ornamental design for a spout end, substantially as shown.
